UNITED STATES PATENT OFFICE.

FRED J. KLINE, OF NEW YORK, N. Y.

PAPER-PERFORATING DEVICE.

Application filed June 30, 1924. Serial No. 723,080.

This invention relates to paper perforating devices and particularly to devices for perforating letters, bills, documents, and any loose sheets printed or written or the like, 5 ready for filing.

The main object of the invention is to provide an improved device for forming two or more perforations in sheets of paper or the like, and another object is to provide 10 improved means for positioning the sheets to be perforated.

The means I prefer to employ for accomplishing the above-named objects, together with other novel and advantageous features 15 of my improved paper perforating device, are illustrated in the drawings accompanying and forming part of this specification, and in which—

Figure 1 is a plan of a paper perforating 20 device embodying my improvements.

Fig. 2 is a front elevation of the same.

Fig. 3 is a side elevation of the same.

Fig. 4 is a plan of a modified form of my 25 invention.

Fig. 5 is a transverse section of the same taken on the line 5—5 of Fig. 4.

Fig. 6 is a plan of a portion of another modification, and

Fig. 7 is a section taken longitudinally 30 along the gage bar of another modification.

Like reference characters refer to like parts throughout the several figures of the drawings.

As illustrated in the drawings, my 35 improved paper perforating device embodies a base portion indicated by the numeral 1, and which base portion is wider at the rear than at the front and has a plurality of upright portions 2 at the rear, in this instance two, 40 but any desired and practicable number may be used according to the number of perforations desired.

Each of the said upright portions is provided with a vertical bore or bearing 3 in which is mounted a vertically-movable punch 4, the body of which is preferably round and the end for punching holes may be of any desired shape. A hole registering with the punch is formed in a member beneath such as the plate 5 which forms the die for said punch 4.

There is a lever 6 provided with a plurality of branches 7, in this instance two in number, to correspond with the number of punches 4, and there is a knob 8 on the lever by which the same is operated. The

branches 7 of the lever 6 are pivoted by means of pins 9, to the upper parts 10 of the upright portions 2, said portions being narrowed at these parts to fit the slots 11 60 in the branches 7 of the lever 6. The holes 12 in the said portions 2 are made larger than the pins so as to provide for the endwise movement of the lever when it is pushed down to effect the punching or perforating. 65 The punches 4 are pivotally connected to the lever branches 7 by pins 13, and there are spring pockets 14 and 15 in the upright portions 2 and the lever branches 7 respectively, and there are springs 16 held in said 70 pockets and coiled around the punches to normally hold the lever 6 and punches 4 in their retracted position. The upper ends of the punches 4 preferably bear against the upper faces of the pockets 15 so that great 75 force may be exerted on the lever 6 without springing or breaking the pins 13.

It is very advantageous to provide special means to position the sheets of paper when the same are being perforated, and the 80 means I prefer to employ for this purpose are illustrated particularly in Figs. 1, 2 and 3 of the drawings.

The base portion of the device is provided with a channel or groove 18, and in said 85 groove is a gage bar 19, preferably with a gaging portion 20, and it may also be notched on the side edges as at 21. In order to hold the gage bar 19 properly in the groove 18, there is a plate bearing yieldingly on the top 90 of the said bar, and in this form of the invention the die plate 5 extends forward far enough to cover the groove 18 and a portion of the gage bar 19 therein. A screw such as 23 may be placed in the forward part of 95 the plate 5 and by means of said screw the plate can be brought to bear on the gage bar to different degrees so that said bar is held by friction of the several parts after it has been moved to any desired position along 100 said groove. There is a trigger 24 pivoted on a boss 25 on the side of the base portion 1, and there is a detent portion of said trigger which is preferably pointed so as to engage with the notches 21 when pressed toward the same by means of the spring 26. If it is desired to perforate standard size 105 sheets, the notches and detent may be used.

The operation of using the above-described gage bar for gaging or positioning the paper 110 to be perforated, is to set the gaging portion 20 by pushing it to the proper position, and

then to locate the sheets of paper by placing them with their right hand edges against the said gaging portion 20. The knob 8 is then pressed down and the perforating of the sheets is effected. When the spring pressed trigger 24 is used, it automatically moves into the proper notch when the same is moved opposite to it on moving the bar 19.

Figs. 4 and 5 illustrate a modified form of 10 gage bar and the holding means therefor. In this construction the gage bar 19 is beveled at 28 on each side throughout its length and is held in position by the front edge of the plate 5 and the rear edge of the bar 29 15 which are beveled to conform to the edges 28. Screws 30 are provided to secure the bar or strip 29 in place and to vary the friction of the same on the adjacent edge of the gage bar 19 so that said bar can slide with greater 20 or less facility as desired. A spring plunger 31 is provided which is adapted to engage with the notches 21 in the side edges of the gage bar 19.

In the form of the gage bar shown in 25 Fig. 6, two springs 32 are provided to secure sufficient friction on the gage bar 19 but otherwise the construction is similar to that in Figs. 4 and 5 except that the bar 29 and the spring plunger 31 are omitted and the 30 channel 18 for the gage bar 19 is arranged to allow some play or looseness and the necessary resistance to hold it in its set positions is obtained from the said springs 32.

Fig. 7 illustrates another mode of giving 35 frictional resistance to the gage bar. In this form the gage bar 19^a is curved downwardly as at 19^c and the depth of the channel 18 is such that the plate 5 when secured in place exerts pressure on the bar 19^a to slightly compress the portion 19^c thus giving a stated amount of friction to retain said bar in the desired positions. The bar may also be curved at the parts 19^a and 19^c to give more working length to the bar 19^a with the same frictional effect.

What I claim is:—

1. The combination with a paper perforating device having a base embodying a plurality of upright portions, each having a pivot fulcrum, a vertical punch bearing and a spring pocket, of a lever having a plurality of branches, and a knob in the portion connecting such branches, a plurality of pivots one on each lever branch for pivoting the 50 same on said upright portions of the base which pivots are less in diameter than the fulcrums and movable laterally therein, a plurality of punches, one for each of said bearings, a plurality of transverse pins joining the punches to the lever branches, and a plurality of springs, one in each of said 55 spring pockets bearing against said transverse pins, for retracting the lever and punches.

2. The combination with a paper perforat-

ing device provided with a base portion having a lever fulcrum which permits lateral movement of the lever pivot axis when the lever is oscillated on the same, of a lever fulcrumed by means of said fulcrum and 70 having endwise movement at the fulcrum end when oscillated, a lever pivot secured to the part of the lever next the fulcrum and movable laterally in said fulcrum when the lever is oscillated and with the lever in its 75 endwise movement, a punch jointed to the lever and movable vertically only by the same, and a die secured to the base portion under the punch and cooperating with said punch.

3. In a paper perforating device, the combination with a base portion provided with a transverse groove, of a vertically movable punch, a die plate having a perforation in line with and cooperating with the punch 85 and a portion extending over said groove and secured to the base portion at one side only of said groove, and a gage member 90 slideable in said groove and normally held in position therein by the inherent resiliency of said die plate.

4. The combination with a paper perforating device having a base, of a lever pivoted thereon which has endwise movement when oscillated, punches movable vertically only and jointed to said lever, a die plate under and alined to the punches and secured to the base, and means for positioning the paper to be perforated which include a gage 100 bar slideable under the paper having a gage portion at one end and spacing means including elements spaced along its length and a member secured to the base of the device to cooperate with said elements.

5. The combination with a paper perforating device having a base portion, of means for positioning the paper to be perforated which embody a gage bar slideable in a channel in said base portion, and means to slidably hold the gage bar in said channel which embody a plate over the channel and means to hold said plate which include a screw at one side to cause pressure of the same on said gage bar to different degrees.

6. The combination with a paper perforating device having a base portion, of means for positioning the paper to be perforated which include a gage bar slideable under the paper and having a gage portion at one end and notches spaced along its length, and a trigger pivoted on the base portion and having a detent portion adapted to engage with said notches.

7. The combination with a base member having two upright portions each provided with a pivot fulcrum and an overhanging portion having a vertical punch bearing, and a die plate secured to said base member and having two perforations respectively under said overhanging portions and alined to said 130

punch bearings, of a two branched lever, two punches one for each lever branch and movable vertically only in said punch bearings, two pins whereby the punches are connected 5 to the respective lever branches, and two pivot pins one for each lever branch for pivoting the lever on said upright portions, smaller in diameter than said pivot fulcrum to permit lateral movement of the pins when 10 the lever is oscillated and endwise movement of the lever.

8. The combination with a base having two upright portions each having a pivot fulcrum and an overhanging portion provided with a vertical punch bearing, of two punches movable vertically only in said punch bearings, a die plate secured to the base and having two perforations respectively under and registering with said 20 punches, a lever having two branches each jointed to a punch by a pin and each branch having an additional surface over the punch for operating the latter, and two pivot pins whereby the lever branches are pivoted in 25 the fulcrums in the rear of the punches and which pins have a lateral movement in conjunction with end-wise movement of the lever when the same is oscillated.

9. The combination with a paper perforating device provided with a base portion having a lever fulcrum which permits lateral movement of the lever pivot axis when the lever is oscillated on the same, of a lever fulcrumed by means of said fulcrum 35 and having endwise movement at the fulcrum end when oscillated, a lever pivot secured to the part of the lever next the fulcrum and movable laterally of the fulcrum when the lever is oscillated and with the 40 lever in its endwise movement, a punch connected to the lever by a joint pin and movable vertically only by the same by means of the joint pin and an additional surface on the lever over the punch, and a die secured to the base portion under the punch 45 and cooperative with the latter.

10. A paper perforating device comprising a base having a plurality of upright portions, a vertical punch bearing in each of 50 said uprights, a plurality of punches, one

slidable in each of said bearings, a lever having a plurality of branches, a pivot joining each of said branches to each of said uprights, whereby the lever may be oscillated, and a pivot pin joining each of said punches 55 to each of the branches of said lever, said lever branches each having a cam surface contacting with the upper end of each of said punches, whereby a downward punching force exerted on said lever is transmitted 60 to each of said punches through its respective cam surface and pivot pin.

11. The combination with a paper perforating device having a base provided with a plurality of upright portions each having 65 a punch bearing, of a plurality of punches, one slidable in each of said bearings, said upright portions each having a pivot fulcrum, a lever having a plurality of branches each connected to one of said punches, and a 70 plurality of fulcrum pins, one connecting each of said lever branches to one of said upright portions, said fulcrum pins being of less diameter than said fulcrums and transversely movable therein, whereby said lever, 75 when oscillated, is capable of endwise movement transverse to the axis of said punches.

12. The combination with a paper perforating device having a base provided with a plurality of upright portions each having 80 a punch bearing, of a plurality of punches, one slidable in each of said bearings, said upright portions each having a pivot fulcrum, a lever having a plurality of branches each connected to one of said punches, each 85 of said branches having a cam surface contacting with the upper end of one of said punches, and a plurality of fulcrum pins, one connecting each of said lever branches to one of said upright portions, said fulcrum pins 90 being of less diameter than said fulcrums and transversely movable therein, whereby said lever, when oscillated, is capable of endwise movement transverse to the axis of said punches. 95

Signed at New York, in the county of New York, and State of New York, this 24th day of June, 1924.

FRED J. KLINE.
